UNITED STATES PATENT OFFICE.

JOHN C. FORSTER, OF PITTSBURG, PENNSYLVANIA.

DESIGN FOR A GAS-STOVE.

No. 37,531.

Specification for Design.

Patented Sept. 5, 1905

Application filed July 27, 1905. Serial No. 271,547. Term of patent 7 years.

To all whom it may concern:

Be it known that I, JOHN C. FORSTER, a citizen of the United States, residing at Pittsburgh, Allegheny county, Pennsylvania, have invented a certain new, original, and ornamental Design for a Gas-Stove, as shown in the accompanying drawing, which is a view in perspective of the same.

I claim—
The ornamental design for a gas-stove, as shown.

JOHN C. FORSTER.

Witnesses:

MARGARET HUGHES,
J. M. NESBIT.
